US00D905658S

(12) **United States Design Patent** (10) **Patent No.:** **US D905,658 S**
Levine (45) **Date of Patent:** **** Dec. 22, 2020**

(54) **ADJUSTMENT PORTION OF A HEADPHONE DEVICE**

(71) Applicant: **New Audio LLC**, New York, NY (US)

(72) Inventor: **Jonathan E. Levine**, New York, NY (US)

(73) Assignee: **New Audio, LLC**, New York, NY (US)

(**) Term: **15 Years**

(21) Appl. No.: **29/695,994**

(22) Filed: **Jun. 24, 2019**

Related U.S. Application Data

(63) Continuation of application No. 29/636,718, filed on Feb. 9, 2018, now Pat. No. Des. 857,654, which is a continuation of application No. 29/583,762, filed on Nov. 8, 2016, now Pat. No. Des. 812,588, which is a continuation of application No. 29/532,834, filed on Jul. 10, 2015, now Pat. No. Des. 772,841, which is a continuation of application No. 29/481,794, filed on Feb. 10, 2014, now Pat. No. Des. 736,174.

(57) **CLAIM**

The ornamental design for an adjustment portion of a headphone device, as shown and described.

DESCRIPTION

FIG. 1 is a perspective view of an adjustment portion of a headphone device showing my new design.

FIG. 2 is a front elevational view thereof.

FIG. 3 is a back elevational view thereof.

FIG. 4 is a first side elevational view thereof.

FIG. 5 is a second side elevational view thereof.

FIG. 6 is a top plan view thereof; and,

FIG. 7 is a bottom plan view thereof.

The broken lines depict environment that forms no part of the claimed design.
